TRAFFIC SIGNAL

Arthur Douglas Johns, Jr., Vancouver, British Columbia, Canada

Application May 3, 1934, Serial No. 723,693

1 Claim. (Cl. 177—337)

My invention relates to improvements in neon-sign, highway-crossing signals and timers, and has for an object to provide neon illuminating gas tubes in suitable shapes for automatic highway and street-crossing signals, replacing the electric lamp and colored lenses of present use.

Another object of my improvement is to replace the legends on the said colored lenses, as well as the lenses themselves, with neon light-tube letters.

Another object of my improvement is to provide, as a part of the automatic signals, extensions of the gas light tubes which are illuminated in fractional parts, additively or subtractively, thus visibly indicating automatically the part of the crossing period past and remaining at any time of observation.

Another object of my improvement is to provide an automatic crossing signal which is not illuminated, in the operative colors thereof, by the direct rays of the sun.

Another object of my improvement is to provide an electric street-crossing signal operating automatically with less electric current than is now required.

Another object of my improvement is to provide an electric street-crossing signal of more pleasing appearance than those now in use.

Other objects of my invention will appear as the description thereof proceeds.

I attain these and other objects of my improvement with the device illustrated in the accompanying two sheets of drawings, which form a part of this specification, in which Figure 1 is a plan view of my signal box in section on the line 1—1 of Fig. 2 and a plan view of the signal operating apparatus, Fig. 2 is the front or east side elevation of the signal, Fig. 3 is north side elevation of the signal, Fig. 4 is the rear side elevation of the bell-control mechanism, Fig. 5 is a segregated front elevation of the switch board, drawn on a larger scale, Fig. 6 is a front elevation of the segregated switch arms, drawn on a larger scale, Fig. 7 is an edge elevation of Fig. 6, Fig. 8 is an end view of the longer switch arm taken from Fig. 7, Fig. 9 is an end view of the shorter switch arm taken from Fig. 7, Fig. 10 is a plan view in section of a fragment of the switch board on the diagonal line 10—10 of Fig. 5, Fig. 11 is a side elevation of the outer end of the timer tube, the remainder being broken away, in section on a medial plane, Fig. 12 is a diagram of the electrical connections for the red signals, and Fig. 13 is a diagram of the electrical connections for the green signals.

Similar characters indicate similar parts in

the several views. Certain parts are broken away to show other parts hidden thereby.

With more particular reference to designated parts:

The frame for the signal box consists of four angle bars having the webs 14, 14 and the relatively wide flanges 15 set vertically at each box corner with the flanges projected diagonally outward and curved inwardly at the upper part of the frame to be joined at the vertical center line 16 of the box and fastened beneath the ornamental flange 145 of support pipe 146.

The bottom ends of the said corner angle bars are fastened to the square frame made by the four bottom bars a14. The frame is covered with 18 sheet metal side plates 17 and dome plates 18 fastened along their edges to the frame angle bars and bottom bars, the dome sheets 18 overlapping the tops of the side sheets 17. All of these cover sheets or plates are preferably fastened by screws through the plates and engaged in tapped holes in the box frame, providing for their easy removal.

A floor 16 is fastened to the frame at the spring of the dome curves providing a top room in the 25 box for the signal operating apparatus the several parts of which are shown in plan view in Fig. 1. Access to this apparatus room is easily had by removing one or more of the plates 18.

The flat rectangular cover plates 17 each provide a bag on which are mounted two similar shaped signal tubes disposed one above the other. The signal tubes on the east plate 17 will first be described. Near the bottom of the plate at a19 are the tube letters GO. One end of the tube 35 begins in letter O at 41. From the letter G the tube is extended in two concentric circles 19 around the tube letters GO, finishing its circular shape at 43 from which point the tube is extended upwardly in an outward curve at 43 to its other 40 end at 51. This is one of four similarly shaped signal tubes which are reserved for green starting signals on the four sides of the box near the bottom. The one on the north side being shown in Fig. 3 at a23, 23, 24. The central letters and 45 the enclosing part of the tube 19 constitute the main signal part of the tube while the part 43 is the timer extension thereto.

On the upper part of the east plate 17 at a27 are the tube letters

50

ST
OP

relatively disposed as typed. One end of this tube begins at 75 in the letter P and is extended 55

from the letter T in two concentric circles 27 around the said letters to the point 73 from where the tube is extended downward in an outer curve to its other end at 65. This is one of four 5 similar shapes of tube signals reserved for the red stop signals disposed on four sides of the box near the top. The one on the north side is shown in Fig. 3 at a31, 31, 32.

The only difference between the signal tubes 10 at the top and bottom of the sides of the signal box resides in the tube letters at the center of the coil, and one of the tubes is revolved through an angle of 180° relative to the other. The continuation of the tubes between the said tube letters is indicated by dotted lines in Figs. 2 and 3. 15 These parts of the tubes are made opaque in order that the visible light may be confined to the letter shapes, as is well known in the art. The central letters and the enclosing part of the tube 20 27 constitute the main signal part of the tube while the part 65 is the timer extension thereto.

A sectional view of a portion of one of the tubes with two electrodes thereon is shown in Fig. 11, where the electrode a63 is attached to one end of the tube 24 and the electrode a61 is attached to the same tube a short space therefrom. The electrode housing 63 is a short glass tube attached to the main tube 24 by welding. Likewise the electrode housing 61 is attached 30 by welding to the tube 24. The wires joined with the electrodes a63 and a61 are extended through the conical ends of the housings 63 and 61 in which they are hermetically sealed. The several electrode housings shown in Fig. 2 are so 35 small that no attempt is made to indicate that each must have a metal electrode within attached to the wire indicated as entering the tapered end of each one thereof. Since it appears to be a common practice in the art to refer 40 to the electrode housing and the electrode enclosed thereby as "the electrode", the electrodes shown in this specification by their housings only will be referred to as electrodes.

Attached to the tube a23, 23, 24 are, beginning 45 with the end of the tube from which the letter O is shaped, the electrodes 53, 55, 57, 59, 61 and 63, the latter being at the other end of the tube, as shown in Figs. 2 and 3. In Fig. 2 side elevations of all of these electrodes are shown in solid 50 lines.

Attached to the tube a31, 31, 32 are, beginning 55 with the end at the letter P, the electrodes 87, 85, 83, 81, 79 and 77, the last electrode being at the other end of the tube as shown in Figs. 2 and 3. A side elevation in solid lines of the electrodes of the tubes a23, 23, 24 and a31, 31, 32 is shown in Fig. 2, except the electrodes 83, 81 and 79 which are hidden in the drawing by the electrodes 61, 59 and 57 respectively.

60 In the wiring diagrams of Figs. 12 and 13 the tubes are represented as straight and foreshortened but to each is attached the full number of electrodes related thereto with their individual designating characters.

65 In Fig. 1 the red tubes are shown in top edge elevation on the four sides of the signal box as well as a part of the green tubes disposed below the red tubes.

As will be fully explained later, the tangent 70 extensions 29, 22, 23, 26, 28, 30, 32 and 34, each with five electrodes attached, are used to indicate, visibly, subdivisions of the signal periods.

The switch board 35 with base 36 is fastened 75 in a vertical position to the floor 16. The bell switch bracket 122 is disposed parallel with the

switch board 35, with their central bearings aligned, and fastened to the floor 16. The switch shaft 37 is mounted for revolution in the said central bearings of the switch board and bell switch bracket with its ends protruding beyond 5 both the said switch board and bell switch bracket. The friction disc 116 is mounted on the shaft 37 and fastened thereto for revolution therewith. The slow-speed electric motor 115 has base lugs a115, one of which has a threaded hole therein, 10 and is mounted on base 119 with the said lugs extended through a central longitudinal guide slot in the base. The setting screw 120 is mounted for revolution in the base 119 and is extended through the lugs a115 being engaged threadwise 15 with the said threaded lug. The screw 120 is disposed parallel with the motor shaft 116 and has the handle 121 with which it may be revolved to move the motor 115 forward or backward longitudinally to desired positions where- 20 in the screw will retain the motor as desired. The motor shaft 116 has the friction disc 117 fastened on its outer end to revolve therewith and is disposed at right angles with and in the plane of the shaft 37 with the disc 117 bearing on the 25 disc 118. The construction provides for driving the shaft 37 by the motor 115 at speeds determined by the position of the driving disc 117 on the driven disc 118 which position is controlled by revolving the screw handle 121. 30

On the end of switch shaft 37 which protrudes beyond the switch board 35 is fastened the double switch arm 37, 38 to be revolved thereby. The switch arms 37 and 38 are radial to the switch shaft and aligned with each other. On the outer end of longer switch arm 37 is fastened wider switch brush 39 and on the outer end of shorter switch arm 38 is narrower switch brush 40.

On the outer surface of the switch board 35, which is of electrically insulating material, are 40 two concentric rows of switch blocks with an intervening buss ring, a concentric buss ring within the smaller row of switch blocks and two extra switch blocks outside of the larger row of blocks diametrically disposed relatively. The 45 assembly of blocks and buss rings comprise four separate complete switches.

Fastened on the floor 16 are the two tube-lighting converters, one with primary coil c113 and secondary coil b113 and the other with primary coil c114 and secondary coil b114. The primary coils of both are connected to the service wires 141, 142 shown as entering the support pipe 146 in Figs. 2 and 3. The secondary coil b113 has the terminals a113 and b113 of which terminal b113 55 is connected with the buss ring 89 and the terminal a113 is connected with the four electrodes 75, 73, 81, 83 on the inner ends of the four red tubes 21, 29, 31 and 33 respectively, as shown in Fig. 12; and the secondary coil b114 has the terminals a114 and b114 of which terminal b114 is connected with the buss ring 100 while terminal a114 is connected with the inner ends of the 60 four green tubes 19, 21, 23 and 25 through their electrodes 41, 42, 53 and 54 respectively, as shown 65 in Fig. 13.

The switch board 35 is divided into right and left halves by a central vertical line not shown, and each half is divided into six 30° sectors. Beginning at the top of the right half the switch 70 blocks 90, 91, 92 and 93 are centrally disposed in four of the first 30° sectors while the block 94 is disposed in the last two of the said 30° sectors. Beginning at the bottom of the left half the switch blocks 95, 96, 97 and 98 are centrally 75

disposed in the four of the first 30° sectors while the block 99 is disposed in the last two of the said 30° sectors. The long blocks 94 and 99, being diametrically disposed, occupy two of the 30° sectors for reasons to be explained.

Beginning at the bottom in the left half of the inner row of switch blocks, the blocks 101, 102, 103, 104 and 105 occupy the first five of the 30° sectors while the sixth sector is vacant. Beginning at the top in the inner row of the right half the blocks 106, 107, 108, 109 and 110 occupy the first five 30° sectors of this half while the sixth sector is vacant. In the same sectors as the said vacant spaces in the inner row of switch blocks 15 are the two diametrically outermost blocks 112 at the top of the left half and 111 at the bottom of the right half of the switch board. The blocks 111 and 112 are confined to one 30° sector rather than occupying two such sectors as do the adjacent blocks 94 and 99.

In the wiring diagram Fig. 12 the switch blocks in the outer circle and the said two outermost blocks are ranged along the two sides of the bus bar 89 while in Fig. 13 the blocks of the inner circle are ranged along the two sides of the bus bar 100. In Fig. 12 the block 90 is connected with the electrodes 73 and 74, the block 91 with the electrodes 71 and 72, the block 92 with the electrodes 69 and 70, the block 93 with the electrodes 67 and 68, the block 94 with the electrodes 65 and 66, the block 95 with the electrodes 25 and 86, the block 96 with the electrodes 83 and 84, the block 97 with the electrodes 81 and 82, the block 98 with the electrodes 79 and 80 and the block 99 with the electrodes 77 and 78, while the outer block 111 is connected with the block 99 and the outer block 112 is connected with the block 94.

In Fig. 13 the block 110 is connected with the electrodes 51 and 52, the block 109 with the electrodes 49 and 50, the block 108 with the electrodes 47 and 48, the block 107 with the electrodes 45 and 46, the block 106 with the electrodes 43 and 44, the block 105 with the electrodes 63 and 64, the block 104 with the electrodes 61 and 62, the block 103 with the electrodes 59 and 60, the block 102 with the electrodes 57 and 58 and the block 101 with the electrodes 55 and 56.

50 The switch arm brush 39, on the longer switch arm 37, may separately make electrical connection between the buss ring 89 and any one of the switch blocks in the outer circle as it is revolved by the shaft 37; also it may make electrical connection between the outer block 111, the block 94 and the buss ring 89 during its movement over one half the length of the long block 94, and between the outer block 112, the block 99 and the buss ring 89 during its movement over one-half the length of the long block 99.

The switch brush 40 on the shorter switch arm 38 may separately make electrical connection between the buss ring 100 and any one of the blocks in the inner circle and also bear on either of the two vacant sectors in the inner circle of blocks thus at such time connecting the buss ring 100 with no switch block.

70 The switch brushes are shaped to bridge the spaces between the blocks and make no interruption in the passage of electricity as they pass from block to block. The brushes 39 and 40 simultaneously make connections on the switch board at all parts of their revolution except when the brush 40 bears on either of the said vacant sectors in the inner circle of blocks at which

times the outer brush 39 alone is operative in making electrical connections.

In Fig. 2 the switch brush 39 is shown disposed to make electrical connection between buss ring 89 and the switch block 91 thus providing for the flow of electricity from the electrodes 75 and 76 through the red tube coils a27, 27 and a29, 29 to their electrodes 71 and 72, respectively; thus showing a red light in these and in the first space of the time indicators 28 and 30, located on the east and west sides of the signal box, as indicated in the letters

ST
OP

15 the coil 27 and the first section between the electrodes 73 and 71 of the time indicator 28 in Fig. 2. At the same time the switch brush 40 is shown in Fig. 2 as making electrical connection between the bus ring 100 and the switch block 102 of the inner circle; thus showing a green light in the letters and coils a23, 23 and a25, 25 and in the first sections of the time indicators 24 and 26, as shown in the diagram Fig. 13 where the current would flow from the electrodes 53 25 and 54 to the electrodes 57 and 58 respectively. The letters GO and the coils 23 and 25 and the time indicators 24 and 26 to their electrodes 57 and 58, respectively, on the north and south sides of the signal box would show a green light as indicated on the north side of the box in Fig. 3.

30 Assume the switch brush 39 to be turned to contact with the block 92 while the brush 40 contacts the block 103, then by following the charts it is seen that the said red and green signals would be extended in the time indicators to the electrodes 69 and 70 in the red and to the electrodes 59 and 60 in the green. Meanwhile, since the brush 39 retains contact with the buss ring 89 and the brush 40 retains contact with the buss ring 100 the illumination in the red and green tubes, as above described, continues, the only change being that another section of the time indicators is added to the prior illuminated parts of the tubes. Thus, as the rotation of the switch 45 arms continues, diametrically opposite switch blocks in the outer and inner circles are contacted by the brushes and current passes through them to the tube electrodes connected therewith, thus continuing to add section to section of the 50 illumination of the time indicators till the switch blocks 94 and 105 are contacted by the brushes 39 and 40, respectively, when the red tubes on the east and west sides and the green tubes on the north and south sides are completely illuminated.

55 The brush movement continues till the brush 40 passes off of the block 105 on to the blank space between blocks 105 and 106 thus interrupting the current in the green tubes and the illumination therein ceases. Meanwhile, the brush 39 continues its contact with the long block 94 and the illumination in the red tubes on the east and west sides continues.

60 At the time when the brush 40 is entirely on the said blank space the brush 39 contacts the outer block 111 while retaining contact with the block 94 and buss ring 89. From the chart Fig. 12 is seen that the block 111 is connected with the block 99 and the block 99 is connected to the electrodes 77 and 78. Thus, at the moment that the green lights go out the red tubes on the north and south sides of the signal box are illuminated for their entire length, and the signal period is closed by stopping all vehicular traffic by 75

red signals on the four sides of the box as customary with this class of signals.

The switch arms continue to revolve bringing the brush 39 in contact with the block 95, which 5 connects with the electrodes 85 and 86 at the part of the red coils 31 and 33 where the time indicators 32 and 34 are tangent to the coils, illuminating the letters

10 ST
OP

and the coils 31 and 33 on the north and south sides of the box with red light as the brush passes from the outer block 111, but providing no light for the full length of the time indicators 15 32 and 34. Meanwhile, the brush 40 is passing over the block 108, which is connected to the electrodes 43 and 44, thus illuminating with green light the letters GO and the coils 19 and 21 on the 20 east and west sides of the signal box but only to the said electrodes 43 and 44 which are on the coils at the parts where the time indicators 20 and 22 are tangent thereto, thus providing no light for any part of these time indicators. The 25 brush 39 passes over the block 96, which is connected to the electrodes 83 and 84 thus continuing the red illumination of the letters

ST
OP

30 the coils 31 and 33 and to these adding the first section of the time indicators 32 and 34 on the north and south sides of the box. Meanwhile the brush 40 is passing over the block 107, which is connected with the electrodes 45 and 46, thus continuing the green illumination of the letters GO, 35 the coils 19 and 21 and the adding thereto of the green illumination of the first section of the time indicators 20 and 22 on the east and west sides 40 of the signal box. The brush 39 then moves over the signal block 97, which is connected with the electrodes 81 and 82, thus retaining the red illumination of the letters

ST
OP

45 the coils 31 and 33, the first section of the time indicators 32 and 34 and adding thereto the second section of the said time indicators on the north and south sides of the box. Meanwhile, the brush 40 is moving over the block 108, which is connected with the electrodes 47 and 48, thus continuing the green illumination of the letters GO, 50 the coils 19 and 21, the first section of the time indicators and adding thereto the second section of the said time indicators 20 and 22 on the east and west sides of the signal box. The brush 39 then moves over the block 98, which is connected with the electrodes 79 and 80, thus adding 55 the third section of the time indicators 32 and 34 60 to the red illuminated second and first sections thereof to the coils 31 and 33 and to the letters

ST
OP

65 therein on the north and south sides of the signal box. Meanwhile, the brush 40 moves over the block 109, which is connected with the electrodes 49 and 50, thus adding the third section of the time indicators 20 and 22 to the green illumination 70 of the first two sections thereof, to the coils 19 and 21 and the letters GO therein. The brush 39 then passes over the first part of the long block 99, which is connected with the electrodes 77 and 78, thus adding the fourth and last section 75 of the time indicators 32 and 34 to the red illu-

minated third, second and first sections thereof, to the coils 31 and 33 and to the letters

ST
OP

therein on the north and south sides of the switch box. Meanwhile, the brush 40 passes over the block 110, which is connected with the electrodes 63 and 64, thus adding the fourth section of the time indicators 20 and 22 to the green 10 illuminated tubes which completes illumination 15 thereof and the entire length of the green-signal tubes is operative. Continued movement of the brush 40 causes it to pass from the block 110 on to the blank space between this block and 20 the block 101 shutting the current from the said green signal tubes on the east and west sides of the box and their color disappears. Meanwhile the brush 39 continues on the long block 99 and also contacts the outer block 112, which is connected with the block 94, thus the red tubes on the north and west sides of the box continue as such but also the upper tubes on the east and west sides of the box are made red, resulting in the red illumination of all of the upper tubes 25 and no illumination in any of the lower tubes, which marks the closing of a time period. The brush 39 moves from the long block 99 and the outer block 112 on to the block 90, which is connected with the electrodes 73 and 74, thus the 30 top tubes on the north and south sides of the box lose their red color and the top tubes on the east and west sides of the box are illuminated red beginning with the letters

ST
OP

35 and ending with the beginning of the tangent time indicators 28 and 30. Meanwhile the brush 40 has passed on to the block 101, which is connected 40 with the electrodes 55 and 56, and the lower tubes on the north and south sides of the box are illuminated green beginning with the letters GO and ending with the beginning of the tangent time indicators 24 and 26.

45 An entire revolution of both brushes 39 and 40 has now been followed and the operations of the signals thereby have been given in detail together with the required electrical conduits and connections with respect to the signal control switch board 35 and the brushes 39 and 40 which are slowly moved thereover by the revolution of the motor 115.

It is now plain that the construction provides for a four-sided signal box with a signal tube for red illumination above and a signal tube for green illumination below on each of the four box sides, and with red signals displayed on two opposite sides of the box simultaneously with green signals displayed on the other two opposite sides 55 of the signal box. The signal period is subdivided into six divisions. During the first division both the red and green illuminations are confined to the signal letters and the coils around the same, during the second division the illumination of the first spaces of the time indicators is added, during the third division the second spaces of the time indicators are added, during the fourth division the third spaces of the time indicators are added, during the fifth division the fourth and last spaces of the time indicators are added and during the sixth division the green signal lights 60 disappear and all of the red signals are on.

65 In some cases where these crossing signals are used the time indicators will doubtless supersede 70 75

the present signal bells, since they are informative of the part of the time period passed and yet remaining, making the bell signals in some cases unnecessary. However, bell signals are included in this specification.

The bell-control mechanism is shown in Figs. 1 and 4. The bracket 122 is vertically disposed and fastened to the floor 16 and has a central bearing in which is mounted the other end of the switch shaft 37. On one side of the bracket 122 are fastened the blocks of insulating material 123 and 131 disposed on opposite ends of a diameter through the shaft 37. Set at a distance from the block 123 are the spaced pins 127 and 130. The prime current-break spring 124 is fastened to one side of the block 123 tending to react toward the shaft 37 and stopped from nearer approach to the shaft by the pin 127 set in the bracket 122. The contact spring 128 has near one end the contact point 126 on its outer side and the V embossment on its inner side at 125. The second contact or current-break spring 129 is fastened to the other side of the block 123 tending to react toward the spring 124 and stopped from nearer approach thereto by the pin 130 set in the said bracket. Near the free end of the spring 128 is the contact point 129 adjacent the said contact point 126. Fastened to the other block 131 is the prime current-break spring 132 set to react toward the shaft 37 and stopped from nearer approach thereto by the pin 135 fastened in the bracket 122. Near an end of the spring 132 is the V embossment 133 projected toward the said shaft and on the other side thereof is the contact point 134. The second current-break spring 136 is fastened to the other side of the block 131 and is set to react toward the spring 132 and stopped from nearer approach thereto by the stop pin 138 fastened in the bracket 122. The embossments 126 and 133 are on the ends of a diameter through the shaft 37 and equidistant therefrom. The shaft 37 protrudes beyond the bearing in the bracket 122 and has on its protruding end the two fingers 139 and 140 retainable in desired positions on the shaft by set screws. The said fingers are of equal length and during revolution impinge on the embossments 126 and 133 to force the contact point 126 against the contact point 129, thus closing a circuit through springs 124 and 128; and also to force the contact point 134 against the contact point 137, thus closing a circuit through the springs 132 and 136. The construction provides for two contacts of the springs 124 and 128 closely occurring and also for two closely following contacts of the springs 132 and 136 each revolution of the shaft 37.

A wiring diagram in connection with Fig. 4 shows the terminal 143 connected with both of the springs 124 and 132 and the terminal 147 connected with both of the springs 128 and 136.

The converter having a primary coil a144 and a secondary coil 144 is fastened on the floor 16 and its primary coil is connected to the service wires 141 and 142. The terminal b143 of the secondary coil 143 is connected with the terminal 147 of the said circuit-closing springs, the termi-

nal c143 is connected with the bell magnet terminal 149 and the bell magnet terminal 150 is connected with the circuit-closing springs terminal 148. The connections provide for the ringing of the bell 142 every time either of the fingers 139 or 140 causes either of the springs 124 or 132 to contact with either of the springs 128 or 136. As illustrated, the bell 142 will ring when the switch brush 39 contacts switch block 111 and again when the said brush breaks contact with the said block; also, the said bell will ring when the brush 39 contacts the switch block 112 and again when the said brush breaks contact with the block 112, causing the said bell signals to be given at the beginning and end of the signal division when all of the red signals are displayed and none of the green signals appear. If it be desired that the bells shall ring at another part of the time periods, the fingers 139 and 140 may be set at the places in the shaft revolution relative to the switch arms 37, 38 which will ring the bell at the desired times. If the use of the bell be not desired, the fingers 139 and 140 may be removed from the shaft 37.

The converter having the primary coil a144 and the secondary coil 144 is fastened to the floor 16. The terminals of the secondary coil 144 are connected to the terminals of the motor 115, while the terminals of the primary coil a144 are connected to the service wires a141, a142. These service wires are from a switch at the signal-control central station and are brought to the signal box therefrom. The service wires 141, 142 also are from the said central station and are connected to another switch thereat; both of the said switches being connected to the city service wires. If all traffic at a certain street intersection should cease, the motor in the signal box thereat may be stopped at a time when all of the red signals and none of the green signals are being shown, and if it is desired that the bell should continuously ring at the same time, the motor is stopped at a time when the said bell is ringing. This condition of the signals will continue till the motor is again started when the usual signal operation will be resumed.

The relatively wide web on the frame corner T bars is useful in covering an edge view of the signals on the transverse sides of the signal box.

Having thus disclosed my invention, what I claim as new therein and desire to secure by Letters Patent is,—

An illuminating gas-filled tube street-crossing signal capable of emitting a traffic-directive color including, traffic letters formed from the said tube, a part of the said tube being coiled around the said letter part thereof, another part of the said tube being extended from the said coil, a tube electrode connected to the end of the said tube at one of the said letters, a plurality of other tube electrodes spaced apart and connected to the said tube extension, and means to cause an electric current to pass through the said tube being between the said letter electrode and any one of the said electrodes on the said tube extension. 65

ARTHUR DOUGLAS JOHNS, JR.
